UNITED STATES PATENT OFFICE

GEORGE W. ACKERMAN, OF NEW YORK, N. Y.

DESIGN FOR A SPEAKING ATTACHMENT FOR DOORS

Application filed December 12, 1929. Serial No. 33,759. Term of patent 3½ years.

To all whom it may concern:

Be it known that I, GEORGE W. ACKERMAN, a citizen of the United States, and residing at New York, borough of Bronx, county of Bronx, and State of New York, have invented a new, original, and ornamental Design for Speaking Attachment for Doors, of which the following is a specification, reference being had to the accompanying drawings, forming part hereof, and in which—

Fig. 1 is a front elevational view of a speaking attachment for doors showing my new design.

Fig. 2 is an edge view thereof.

I claim:

The ornamental design for a speaking attachment for doors substantially as shown.

GEORGE W. ACKERMAN.
